copartnership composed of Harold L. Bartelt
and Donald E. Bartelt

Application January 11, 1945, Serial No. 117,380

Term of patent 14 years

(Cl. D80—5)

To all whom it may concern:

Be it known that I, Laurier A. Carrière, a citizen of the United States, residing at Rockford, in the county of Winnebago and State of Illinois, have invented a new, original, and ornamental Design for Jewelry Display Box or the like, of which the following is a specification, reference being had to the accompanying drawing forming part thereof.

In the drawing:

Figs. 1 and 2 are an end view and top view of a jewelry display box or the like embodying my new design, and

Fig. 3 is a top view of the box showing the sliding closures in open position to display the contents of the box.

I claim:

The ornamental design for a jewelry display box or the like, substantially as shown.

LAURIER A. CARRIÈRE.
